UNITED STATES PATENT OFFICE

148,507

DESIGN FOR A MOLDED PULP DECOY

Roger T. Williams, Milwaukee, Wis., assignor to
Pulp Reproduction Company, Milwaukee, Wis.,
a corporation of Wisconsin

Application February 25, 1946, Serial No. 126,896

Term of patent 14 years

(Cl. D31—4)

To all whom it may concern:

Be it known that I, Roger T. Williams, a citizen of the United States of America, residing at Milwaukee, in the county of Milwaukee and State of Wisconsin, have invented a new, original, and ornamental Design for a Molded Pulp Decoy, of which the following is a specification, reference being had to the accompanying drawing, forming a part thereof.

In the drawing:

Fig. 1 is a side elevational view of a molded pulp decoy showing my new design; and

Fig. 2 is a top view of the molded pulp decoy.

The characteristic features of my design are shown by means of full lines in the drawing.

I claim:

The ornamental design for a molded pulp decoy, substantially as shown and described.

ROGER T. WILLIAMS.
